United States Patent

Des. 234,279
Patented Feb. 11, 1975

234,279

CHAIR

Harald Relling, % P.I. Langlos Fabrikker A/S,
6201 Stranda, Norway

Continuation of design application Ser. No. 318,995, Dec.
27, 1972. This application June 14, 1973, Ser. No.
370,019

Claims priority, application Norway July 3, 1972

Term of patent 7 years

Int. Cl. D6—01

U.S. Cl. D6—67

FIG. 1

FIG. 6

FIG. 1 is a front perspective view of a chair embodying my new design;

FIGS. 2-4 are elevations of the chair shown in FIG. 1;

FIG. 5 is a plan of the chair shown in FIG. 1;

FIG. 6 is a perspective view of a similar chair embodying my new design;

FIGS. 7-9 are elevations of the chair shown in FIG. 6; and

FIG. 10 is a plan of the chair shown in FIG. 6.

This application is a continuation of my earlier application, Ser. No. 318,995, filed Dec. 27, 1972.

I claim:

The ornamental design for a chair, substantially as shown.
